UNITED STATES PATENT OFFICE.

ALFRED CHARLES OTTO BOCK, OF BROOKLYN, NEW YORK, ASSIGNOR TO FINGER-
PRINT MACHINE CORPORATION, A CORPORATION OF NEW YORK.

FINGERPRINT COMPOUND AND METHOD.

No Drawing.

Application filed June 1, 1921. Serial No. 474,195.

To all whom it may concern:

Be it known that I, ALFRED CHARLES OTTO BOCK, a citizen of the United States of America, residing at Brooklyn, Kings County, New York, have invented new and useful Improvements in Fingerprint Compounds and Methods, of which the following is a specification.

This invention relates to substances for fixing the impression of finger prints and the like upon a paper or other surface whereon a finger or other body has been impressed.

It is to be understood that while the substance forming the subject matter of the present invention is especially useful in connection with the recording of finger prints, it may be employed in connection with other recording.

It has been found that a highly desirable manner of recording prints is to apply a powder to the impressed surface and afterward exposing it to heat whereby the substance of the powder is caused to adhere to or become incorporated with the substance of the impressed object.

I have found that powdered resinous substances are well adapted for the treatment referred to and give an unusually well defined and permanent record.

Records of different colors may be desired and to this end, I may employ a powdered white resin, giving the desired color by aniline or in any other suitable way.

The method employed in using the compound is to make the impression of the finger upon a piece of paper, whereby the natural secretions of the finger or artificial adhesive material, such as oils applied there-

to, form lines upon the paper corresponding to the lines of the finger printed, the resinous powder is then applied to the impressed surface, the superfluous powder, that is to say that which does not adhere to the lines, is removed and the paper then bearing the powder adhering to the finger lines only is subjected to sufficient heat to cause the resin to soften or liquefy and sink into the body of the paper, when on becoming cool it is incorporated with and fixed therein.

As above stated the resinous powder may be white resin powdered and mixed or dyed with any suitable or desired color.

While the invention has been illustrated by a suitable composition it may be varied in various ways without departing from the spirit of the invention which is not therefore, limited to the precise proportions or ingredients specified. Similarly the method is not limited to the precise details recited, but may be varied therefrom without departing from the spirit of the invention.

What I claim is:

1. The method of recording a print which consists in making an impression, applying to the impression a compound containing resin and subjecting the powdered impression to heat.

2. The method of recording a print which consists in making an impression, applying thereto a powdered compound containing powdered white resin and predetermined coloring material and subjecting the powdered impression to heat to fix the same.

In testimony whereof I have signed this specification this 27th day of May, 1921.

ALFRED CHARLES OTTO BOCK.
